(No Model.)

J. REESE.

ROLLING OLD RAILS TO FLAT PLATES.

No. 350,557.

Patented Oct. 12, 1886.

UNITED STATES PATENT OFFICE.

JACOB REESE, OF PITTSBURG, PENNSYLVANIA.

ROLLING OLD RAILS TO FLAT PLATES.

SPECIFICATION forming part of Letters Patent No. 350,557, dated October 12, 1886.

Application filed February 18, 1884. Serial No. 121,201. (No model.)

To all whom it may concern:

Be it known that I, JACOB REESE, a citizen of the United States, and a resident of Pittsburgh, in the county of Allegheny and State of Pennsylvania, have invented a certain new and useful Improvement in Utilizing Old Rails in the Manufacture of Flat Bars; and I do hereby declare the following to be a full, clear, and exact description thereof, reference being had to the accompanying drawings, in which—

Figure 1 indicates a cross-sectional view of an old rail. Fig. 2 indicates a front elevation of a set of rolls adapted to reduce the metal at one side of the head and flange of the rail.

Fig. 3 indicates a front elevation of a set of rolls adapted to flatten and reduce the blank.

The principal object of my invention is to produce a cheap wide flat bar adapted for the manufacture of skelps, sheets, nail-plates, &c., and free from seams, welds, or folds.

The essential features of my invention are, first, reducing the metal at one side of the head and flange and transferring the displaced metal to their opposite side, and then forcing the sides of the channel-blank so formed out laterally to extend the width and produce a flat bar. These features may be secured by the use of rolls provided with grooves of various forms, but most advantageously by the use of the mechanism I shall now proceed to describe.

In the drawings, A indicates a groove adapted to receive the old rail when the latter is entered on its side. This groove is turned so as to reduce slightly the upper part of the flange, and to admit the flow of the displaced metal, or a part of it, into the lower part of the flange, and also to thin and partially reduce the metal in the inner side of the lower part of the head and allow its upward flow into the upper part of the head. This action on the head is preferable in the first pass, but is not necessary. Its only function is to distribute the metal in the head in such a manner as will enable me to make a deeper flange from the metal in the head during the subsequent passes. The grooves B and C are turned in such a manner as to reduce the upper part of the head and flange and permit the displaced metal, or a portion of it, to flow down-

ward and deepen and thicken their lower parts. The groove D is constructed in such a manner as to repeat the action of the grooves B and C on the head and flange, and at the same time reduce the web in thickness in a slight degree 55 to give a smooth flat surface to the under part of the blank. The grooves E, F, and G (shown in Fig. 3) are turned of a suitable form for gradually flattening down the walls of the channel-blank which will be produced by the 60 action of the first set of rolls, and thereby bring the metal to the width desired.

The operation of my improvement is as follows: Old rails are suitably heated and passed through the first groove, which reduces the 65 upper part of the flange and thickens and deepens its opposite side, and at the same time thins the lower part of the head and widens the lower part of the web, the surplus metal going up into the upper part of the head. 70 The bar is then passed into the next groove, which forces the metal down from the upper part of the head and flange into their lower portions. This action is then repeated by passing the bar through the groove C. It is 75 then turned over and entered into the last groove, which reduplicates this action and transforms the blank into a channel, which is transferred to the flattening-rolls and passed through the grooves E, F, and G, which transform it into a wide flat finished bar. 80

In rolling old rails into the flat bars, when the groove is made to correspond with the given shape and size of the rail, the flange may be rolled down without creasing orlapping; but as the size and shape of the flange vary considerably in different forms and weight of rails it is found difficult in practice to produce flats regularly which will not show creases on both sides. Now, as my bars are 90 only rolled down on one side, the other side being filled up and bent over, the finished product will always have, under such circumstances, one perfect side. In other words, even when irregular patterns or sizes of rails or 95 when defective rails are rolled, the bar produced therefrom will only show a defect on one side, while the other will exhibit a perfectly smooth surface.

Having described my invention, what I too

claim, and desire to secure by Letters Patent, | is—

A pair of rolls having passes, the first of | said passes conforming nearly to the shape of | 5 a rail, another to the shape of a channel-bar, | and the intervening ones shaped substantially | as described, jointly with a further pair of |

rolls having passes, the last of which has the | shape of a flat bar, and the preceding ones | shaped substantially as described.

JACOB REESE.
